(57) CLAIM

The ornamental design for a bed, as shown and described.

DESCRIPTION

FIG. 1 is a perspective view of an embodiment of a bed showing my new design;

FIG. 2 is a right side view thereof, the left side view being a mirror image thereof;

FIG. 3 is a front view thereof;

FIG. 4 is a top view thereof;

FIG. 5 is an enlarged view of the leg thereof;

FIG. 6 is a right side elevational view of a second embodiment of a bed showing my new design, the side being shown broken away to indicate indeterminate length, the left side elevational view being a mirror image thereof; and, FIG. 7 is a front elevational view of FIG. 6, the footboard and headboard shown broken away to indicate indeterminate width.

FIGS. 1 to 5 illustrate the bed of my design in the proportions of a King size bed. FIGS. 6 and 7 show that the width and/or the length of the bed of my design is indeterminate. The single broken line portions are for illustrative purposes only and form no part of the claimed design.
